BALANCED GAS LIFT VALVE

Thomas E. Bryan, Fort Worth, Tex., assignor to Otis Engineering Corporation, Dallas, Tex., a corporation of Texas

Application May 4, 1953, Serial No. 352,943

4 Claims. (Cl. 137—155)

The present invention relates to an improved gas lift valve construction.

In the artificial lift method of flowing or producing wells, such as oil wells, it is necessary to admit an unloading pressure fluid from the well casing into the tubing, whereby the well liquids are thus flowed up through the tubing. Also, the well may be produced by admitting the unloading pressure fluid into the tubing and discharging it into the casing where liquids in the well are accumulated, whereby such well liquids may be flowed or produced through the casing.

The efficiency of gas lift operation may be considered or determined in terms of the amount or volume of gas used to produce a given quantity of oil.

It seems obvious that in actual operation only a necessary amount of gas needs be used to "unload" or produce the well. If additional pressure fluid, such as gas, is used over and above this necessary amount, without gaining any benefit therefrom, then the overall efficiency of the gas lift operation is materially reduced and the gas is thus wasted.

The present invention provides a valve construction which is designed so as to admit the amount of pressure fluid necessary to produce the well, under given conditions, but which will prevent the flowing of excess pressure fluid into the well liquid. One manner in which the present construction accomplishes this is by providing a construction wherein the effect of back pressure due to well fluid or liquids on the valve is eliminated so that the valve construction, after it has been operated to admit the necessary amount of pressure unloading fluid to flow the well may close and prevent the passage of additional pressure fluid therethrough.

By way of further example only, and not to serve as any limitation, it may be assumed that the valve construction of the present invention is mounted in a well so as to admit unloading pressure fluid from the well casing into the tubing, whereby the well fluids therein may be lifted to the surface. If the valve is set to operate at say 350 pounds pressure, then when the pressure of the unloading fluid in the casing exceeds this, the valve will open and admit the unloading pressure fluid to the tubing. If the back pressure effect in the tubing maintains the valve open so as to continue to admit the unloading pressure fluid then more pressure fluid will be admitted than that necessary to produce the well. It can be seen that under certain circumstances additional unnecessary quantities of pressure fluid will be drained from the casing so that prior to operation of the valve on its next cycle, it is necessary to replace this drained gas. However, in the present construction the effect of this back pressure is eliminated so that when the pressure applied on the valve in the casing by the unloading pressure fluid falls below the opening pressure of 350 pounds, then the valve will snap shut.

On the other hand, in present valve constructions where the back pressure effect may maintain the valve open so

2

as to continue the injection of the unloading pressure through the valve, many thousands of cubic feet of pressure fluid may be unnecessarily wasted. As a matter of fact, every unnecessary 100 pounds of pressure drained from a 7 inch casing may amount to several thousand cubic feet of gas which must be replaced before reoperation of the valve.

If the unloading pressure fluid is conducted through the tubing to the casing, then the gas in the tubing must be replaced before reoperation of the valve.

An object of the present invention is to provide a gas lift valve construction in which the effect of back pressure is eliminated in the operation of the valve.

A further object is to provide a valve construction in which a selected pressure medium acts to operate the valve.

Still another object of the invention is to provide a valve construction which is operated by the well fluids or liquids to admit an unloading pressure fluid from the tubing to the casing so as to flow the well liquids therein upwardly through the casing.

Still another object of the invention is to provide a valve construction which may be operated by the well fluids or liquids so as to admit a pressure fluid from the casing to the tubing to flow the well liquids upwardly through the tubing.

A still further object of the invention is to provide a valve construction which may be pressure or gas operated so as to admit pressure unloading fluid to flow the liquid in the well upwardly through the tubing.

A still further object of the invention is to provide a valve construction which may be pressure or gas operated so as to admit pressure unloading fluid to flow the liquid in the well upwardly through the casing.

Yet a further object is to provide a valve construction which may be gas or pressure operated to admit such pressure into the liquids in the well so as to flow or produce such well liquids.

Another object of the invention is to provide a valve construction which may be operated by the well liquids to admit a pressure unloading fluid to the well liquids so as to produce or flow such well liquids.

Still another object of the invention is to provide a valve wherein the effect of a selected pressure medium acting on the valve is nullified, whereby it may be operated by another existing pressure.

A still further object of the invention is to provide a valve construction which will admit a pressure fluid, but which will shut after it has admitted the pressure fluid so as to prevent the flow of additional pressure fluid therethrough.

Yet a further object of the invention is to provide a valve construction for wells to admit an unloading pressure fluid including a bellows, a housing about said bellows forming a closed chamber about the bellows; which chamber is charged with gas at a predetermined pressure, a valve member carried by said bellows; an entry for pressure fluid to first act on said valve member to operate said valve, whereby an unloading pressure fluid is then admitted to unload the well.

Still another object of the invention is to provide a gas lift valve, which is pressure charged, wherein the pressure medium acting to open the valve is admitted to the valve to first act on a valve member to operate the valve.

Still another object of the invention is to provide a valve including a piston member which is subject to the back pressure effect of a selected pressure medium, such effect on opposite sides of the piston being counterbalanced.

With the foregoing and other and additional objects

and advantages in mind, attention is directed to the drawings wherein:

Fig. 1 illustrates a schematic arrangement showing one manner of employing gas lift valves for flowing a well;

Fig. 2 is a vertical sectional view illustrating an embodiment of the invention;

Fig. 3 is a vertical sectional view of an embodiment of the invention illustrating a slightly different modification;

Fig. 4 is a horizontal sectional view taken on the line 4—4 of Fig. 2;

Fig. 5 is a horizontal sectional view taken on the line 5—5 of Fig. 2;

Fig. 6 is a horizontal sectional view on the line 6—6 of Fig. 3; and

Fig. 7 is a partial vertical sectional view showing a modification of the form of the invention illustrated in Fig. 2.

Attention is directed to Fig. 2 of the drawings wherein an embodiment of the invention is illustrated. The valve consists of a housing denominated generally by the numeral 3, which housing may be made up of several component parts as illustrated in the drawings. Any suitable manner of joining the component parts together may be used, and as illustrated the valve housing components may be threaded together whereby various parts can be easily replaced. A bellows or diaphragm element 4 is mounted in the housing and the housing forms a chamber 5 about the bellows which may be charged with gas at a predetermined pressure by means of the adapter illustrated generally at 6. It is not believed necessary to give a detailed description of the manner of connecting the bellows in the housing and of charging the chamber with gas at a predetermined pressure, since this procedure is well known in the art. Carried by the bellows 4 by means of the valve stem 7 extending through the housing to the opposite end 8 thereof is a valve member denominated generally by the numeral 9. It is to be noted that the valve stem 7 is secured at one of its ends 10 to the bellows 4 whereby the chamber 5 about the bellows is closed off from the interior of the bellows.

The valve member 9 is provided with a valve head 11 for seating on the seat 12. The seat 12 is provided with an opening 13 whereby communication therethrough is controlled by means of the valve member.

The valve member includes a piston member 14 on the valve stem 7, which piston member is adapted to sealably fit in the housing to prevent or inhibit the passage of pressure from one side of the seal ring 15 to the other side.

It should be understood, of course, that any suitable type seals may be arranged on the piston member 14 so as to engage the inner periphery 16 of the housing and form a sliding sealed connection therewith. The inner periphery 16 of the housing 3 thus joins a cylinder in which the piston member 14 is mounted for reciprocatory motion. The upper end of this cylinder defines an end wall thereof having the valve seat 12 formed therein.

The valve housing as shown in Fig. 2 is provided with inlets 17 and 18 above and below the piston member 14 respectively, whereby a pressure medium may act on top of the valve head 11 on one side of the piston 14, and also act on the opposite side of the piston member 14 by exerting a pressure inside of the bellows 4 and on the exposed surfaces on the valve stem 7 and piston member 14 below the seal ring 15. The area affected by pressure flowing through the opening 17 above the seal ring 15 and the areas affected by pressure flowing through the opening 18 into the housing below the seal ring 15 offset and counterbalance each other.

As may be seen in Fig. 2, the pressure introduced through opening 18 exerts an upward force on piston 14, and a downward force on the diaphragm end wall 10.

The piston 14 has a larger cross-sectional area than does the diaphragm end wall 10, and therefore the upward force on the piston is greater than the downward force on the diaphragm to thus bias the valve member 9 to a closed position. It is this resultant upward bias, due to the pressure introduced through opening 18 and acting on the diaphragm end wall and piston which offsets and counterbalances the downward force which is exerted on the top of valve head 11 by the tubing pressure introduced through the opening 17; otherwise, if this resultant upward bias were not present, the tubing pressure would tend to force the valve member 9 open against the bias of the pressure charged chamber 5. As is obvious, the cross-sectional area of the piston, on which the tubing pressure acts to close the valve member 9, must equal the cross-sectional areas of the diaphragm end wall 10 and the valve seat 13, on which the tubing pressure acts to open the valve member 9, for the effect of the pressure introduced through openings 17 and 18 to be exactly offset and in true counterbalance.

An additional opening 19 is provided in the housing whereby a pressure fluid or the operating pressure medium may pass thereinto to first act on the valve member to operate the valve, whereby communication through the opening 13 is established for unloading the well. By admitting the pressure fluid or the operating pressure medium so as to act on the valve member instead of on the bellows, distortion of the bellows is eliminated.

It should be noted that the operating pressure medium to actuate the valve may be the unloading pressure fluid or it may be the well fluids or liquids, depending upon the type installation desired.

The valve construction illustrated in Fig. 3 is identical with that shown in Fig. 2, however, the inlets above and below the piston are arranged differently, with the inlet for conducting a pressure fluid or pressure medium to operate the valve being shown as arranged in a different position as illustrated at 20. The inlet 17A is shown at the top of the housing in Fig. 3 with the inlet 18A being illustrated in a different position from that shown in Fig. 2.

Fig. 7 illustrates the valve shown in Fig. 2 with the check valve assembly 23 removed. In this connection it should be noted that while the check valve assembly 23 is provided for inhibiting or preventing back flow of well liquid through the valve, it will, for all practical purposes, not affect the equalization of pressure on the piston member 14 above and below the seal ring 15. In other words, practical experience has shown that no check valve under normal well operating conditions will provide an absolute seal so as to prevent the passage of well liquid therearound so as to exert a force on the valve head 11. The invention may be practiced with or without the check valve so far as the back pressure effect on the piston member 14 is concerned. However, with that form of the invention shown in Fig. 7, the check valve assembly is removed in order that the well may be produced in a slightly different manner to be described hereinafter.

It will now be assumed that the valve comprising the invention is mounted on a tubing string 24 extending down into a well, which well has been previously provided with a casing 25 and may be provided with a packer 26 to fill the space between the tubing and the casing so as to form a casing annulus 27.

The valve is connected to the tubing by means well known in the art, and it is not believed necessary to give a detailed description of the manner of connection. However, the tubing is provided with an opening 24' whereby communication between the valve and tubing, and between the casing and tubing is established by means of the openings 13 and 19 in the valve. With the form of the invention illustrated in Fig. 2 or Fig. 7, the valve may be "gas operated, tubing flow." In other words, well liquid in the tubing 24 will exert a pressure through

the opening 17 and through the opening 18, on opposite sides of the piston 14, whereby the back pressure existing in the tubing is counterbalanced. If the chamber 5 has been charged with gas at a predetermined pressure, say 400 pounds, then pressure fluid may be exerted in the casing annulus so as to flow through the opening 19 and act on the valve member. When the unloading pressure acting on the valve member exceeds the loaded pressure tending to maintain the valve head 11 on seat 12, the valve will open whereupon the unloading gas pressure flows through opening 13 and through opening 17 into the tubing.

As the oil in the tubing is being elevated by means of the charge of gas admitted through the opening 17, its weight plus the friction developed by the flow creates a back pressure in the tubing. The effect of this back pressure acts equally on opposite sides of the piston member 14 through openings 17 and 18 so that it is neutralized. In other words, the back pressure does not maintain the valve open an unnecessary length of time so as to drain unusable quantities of gas from the casing annulus 27.

It can be appreciated that only a certain amount of gas is required to lift a certain amount of oil. If the back pressure keeps the valve open and allows it to flow additional unnecessary quantities of gas from the casing, it will be necessary to recharge the casing annulus at the time that the valve is again operated. Also a much larger quantity of gas has been used for producing a given quantity of oil. The excessive amount of unloading gas or pressure admitted through the valve is wasted since it only entered because the back pressure maintained the valve open and it was not necessarily needed to aid in unloading the well.

If the unloading pressure fluid is admitted in a manner so as to aerate the column of well liquids in the tubing the effect of back pressure is relatively unimportant. However, where the quantity of gas flow through the valve into the tubing is great so that a piston of gas is formed to force a piston of oil out, then the back pressure weight of the oil becomes important and unless it were counterbalanced as provided by the construction herein described it would act on valve head 11 to maintain it open and continue the injection of unloading pressure fluid.

Fig. 2 not only illustrates the form of the invention suitable for a "gas operated, tubing flow" manner of flowing a well, but it also illustrates a valve construction which could be used in an "oil operated, casing flow" manner of producing the well. If the valve is to be used in this manner, then, of course, the unloading pressure is injected down through the tubing 24, whereupon it exerts a pressure above and below the piston, which pressures offset each other. The oil which collects in the casing annulus 27 by a means well known in the art would then exert a pressure on the valve member through the opening 19 to first operate the valve and then the unloading pressure would be admitted through the opening 13 to the casing to unload the well through the casing. When the valve is to be used as an "oil operated, casing flow" type of valve the check valve assembly is eliminated, as shown in Fig. 7, for obvious reasons.

Fig. 3 illustrates the form of the invention when the well is to be produced by "oil operation, tubing flow." In the construction illustrated in Fig. 3, and when the well is to be thus produced, the gas unloading pressure in the casing again acts through the openings 17A and 18A on opposite sides of the seal member 15 of the piston member 14 and exerts counterbalancing effects. The oil or well liquid would then act on the valve member to first operate the valve, whereupon the unloading gas pressure would be admitted from the casing annulus through the valve housing by means of inlet 17A and

through inlet 13 and thence through port 19A into the tubing, and then to unload the well.

The form of the invention illustrated in Fig. 3 could also be used where the well is to be "gas operated, casing flow." In this manner of producing the well with the invention, the well liquid would again accumulate in the casing annulus by means well known in the art and exert a pressure on both sides of the piston member 14 through openings 17A and 18A. The effect of this pressure is offset and the unloading pressure in the tubing acts through the opening 19A to first operate the valve and then unload the well by passing the unloading pressure through openings 19A and 13 and thence through opening 17A to the casing.

15 From the foregoing description of the various ways in which a well can be produced with the present invention, it seems readily obvious that a valve is provided which includes a housing with an entry, whereby a pressure medium may first act on the valve member 20 to operate the valve and then admit unloading pressure fluid to unload the well.

Whether the pressure medium to operate the valve be the well liquid or the unloading pressure fluid itself, it is admitted to first act on the valve member and not the bellows. Also, when the valve is used as an oil or well liquid operated type of valve, the unloading pressure fluid has no effect on the opening of the valve, since the valve construction is provided with means whereby this pressure acting on the valve member is offset.

30 Also, where the valve is a pressure or gas operated type of valve, the valve construction is such that the pressure effect of well liquids thereon is eliminated.

From the above statements it is seen that a balanced valve is provided; that is, one wherein the effect of a selected pressure medium is counterbalanced or nullified.

It should be pointed out that the valves and valve seats of the present invention are formed of a carbide construction. Also, a seal ring 30 is provided on the valve stem 7 so that after the valve stem moves a predetermined distance the interior of the bellows will be sealed off for a well known purpose.

Broadly, the present invention relates to a valve construction which eliminates the effect of back pressure so as to obtain more efficient operation.

45   What is claimed is:

1. In a balanced valve, a housing forming a cylinder, an end wall formed at one end of said cylinder, a valve seat formed on one side of said end wall, a valve disposed within said cylinder and adapted to seat within said valve seat, a flexible diaphragm enclosing the other end of said cylinder, a piston mounted for reciprocatory motion in said cylinder, said piston having a larger cross-sectional area than said valve and also having a larger cross-sectional area than said diaphragm, means connecting said piston to said valve, means connecting said piston to said diaphragm, means forming an inlet in said cylinder between said piston and said diaphragm, means placing said inlet in fluid communication with the other side of said end wall, means biasing said diaphragm toward said end wall whereby said valve will normally seat in said valve seat, and means forming an opening in said cylinder between said piston and said valve seat whereby fluid under pressure may be introduced into said cylinder to force said piston against said biasing means to open said valve, thereby allowing said fluid under pressure to pass through said valve seat.

2. In a device as set forth in claim 1, wherein said biasing means comprises means forming a chamber surrounding said cylinder at the end provided with said diaphragm, and an elastic fluid under a predetermined pressure carried in said chamber.

3. In a device as set forth in claim 1 wherein a second seat is formed in said end wall in fluid communication with said first valve seat, a second valve on the other 75 side of said end wall adapted to seat within said second

valve seat, and means biasing said second valve to closed position.

4. In a device as set forth in claim 1 wherein the cross-sectional area of said piston is equal to the sum of the cross-sectional areas of said valve seat and said diaphragm.
